UNITED STATES PATENT OFFICE

161,443

ANTENNA TUNER

James M. Hayden, Crystal Lake, Ill.

Application August 30, 1950, Serial No. 11,995

Term of patent 7 years

(Cl. D26—14)

To all whom it may concern:

Be it known that I, James M. Hayden, a citizen of the United States, residing at Crystal Lake, county of McHenry, and State of Illinois, have invented a new, original, and ornamental Design for an Antenna Tuner, of which the following is a specification, reference being had to the accompanying drawing, forming a part thereof, in which:

Fig. 1 is a plan view of the antenna tuner showing my new design;

Fig. 2 is a front elevational view thereof;

Fig. 3 is a side elevational view thereof;

Fig. 4 is a rear elevational view thereof.

I claim:

The ornamental design for an antenna tuner, as shown.

JAMES M. HAYDEN.
